UNITED STATES PATENT OFFICE.

OTTO BASTIANSEN, OF BROOKLYN, NEW YORK, ASSIGNOR TO WEARITE CHILDREN'S UNDERWEAR MANUFACTURING CORPORATION, OF BROOKLYN, NEW YORK, A CORPORATION OF NEW YORK.

UNDERWAIST.

Application filed March 30, 1922. Serial No. 548,002.

To all whom it may concern:

Be it known that I, OTTO BASTIANSEN, a citizen of the United States, and a resident of Brooklyn, in the county of Kings and State of New York, have invented certain new and useful Improvements in Underwaists, of which the following is a specification.

The invention relates to underwaists for children and more particularly to underwaists of the character adapted to support the lower underwear, such as drawers and skirts. Underwaists of this general character have long been well known.

The object of my invention is to provide an improved underwaist which shall have a flexible and yielding or vertically stretchable waistband formed of a material which will be light and reasonably cool about the waist, said material being preferably balbriggan. The novel underwaist having the waistband of my invention possesses many benefits, one being that strains applied on the buttons result in the waistband stretching in the direction of the strain, and thereby I avoid the tearing of the button from the waistband or injury to the garment supported by the waistband or injury to the waistband itself. The novel waistband with which I equip the underwaist is properly stayed at its edges and also preferably along its longitudinal center so as to avoid undue longitudinal stretching therein.

The invention will be fully understood from the detailed description hereinafter presented, reference being had to the accompanying drawings, in which:

Fig. 1 is a front elevation of an underwaist, laid out flat, constructed in accordance with and embodying the invention;

Fig. 2 is a back view of one end portion of the same;

Fig. 3 is a vertical section, partly broken away, through a portion of the same, taken on the line of the buttons shown in Fig. 4, but in normal condition, and

Fig. 4 is an elevation of a front portion of the underwaist and illustrates the yielding effect of the waistband when a strain is placed on either or both of the buttons, the downward yielding of the waistband shown in Fig. 4 as having taken place, being due to a strain on the lower button.

In the drawings 10 designates the waist as a whole, 11 the front thereof, 12 the side

sections affording armholes, and 13 the back sections constructed to overlap at the back of the wearer and to be detachably connected together at their outer edges by means of buttons 14 and buttonholes 15 of customary character. Along the upper edge of the waist there is a binding 16, and at the front the waist is gathered, as at 17, to adapt the same for the figure of the child. The side sections 12 are of usual type in this class of underwaists and therefore need not be specifically described. In the present instance, however, the side sections 12 do not extend to the bottom of the waist but only to a waistband 18, as shown in Figs. 1 and 2, and which constitutes the more essential feature of my invention. Below the waistband 18 there is a lower waist section 19 which is continuous throughout its length and independent of the side sections 12. The outer end edges of the back sections 13 and lower section 19 and the lower edge of said section 19 are strengthened by a binding 20 secured thereto, this binding at the outer edges of the back sections 13 extending across the end of the waistband 18, and therefore serving as stays and securing means for the ends of said waistband.

The waistband 18 is defined between an upper longitudinal binding strip 21 and a lower longitudinal binding strip 22, these strips being properly spaced apart and holding between them a knitted fabric 23 which is preferably of the material from which stockings and undershirts are frequently made and which is commonly known as "balbriggan." The fabric 23 is in the nature of a single longitudinal strip or band and may be designated as a webbing. The strip or band 23 has limited longitudinal stretch, but is capable of material stretch when strain is brought against it in a vertical direction, and I so dispose the band 23 within the waist of the garment that I may utilize the vertical yielding of the fabric in resisting strains on the buttons while at the same time keeping the fabric under control as to longitudinal stretching. The fabric 23 is held at its ends by the binding 20, as hereinbefore explained, and at its upper and lower edges by the bindings 21, 22 by which the fabric 23 is secured, by sewing, to the front, side and back sections 11, 12, 13, respectively, and lower longitudinal section 19. By preference I apply upon the

outer face of the fabric 23 a longitudinal straight stay-strip 24 which serves to increase the strength of the band 23 and as means for receiving tapes 25 for holding the 5 upper buttons 26, said buttons 26 being intended to support a child's skirt.

The lower longitudinal binding 22 serves as means for receiving tapes 27 for the lower buttons 28 and also as means for receiving 10 the tapes 29 by which the loops 30, for garter supporters, are held.

My invention resides more particularly in an underwaist having the waistband 18 of the particular kind I have described and 15 a lower continuous section 19, said waistband comprising the knitted fabric 23 disposed as described and secured by upper and lower binding strips 21, 22. Preferably I will make use of the longitudinal stay- 20 strip 24, but do not wish to be limited in every instance to the presence of the strip 24.

I illustrate in Fig. 4 one of the benefits of my invention. In Fig. 4 I illustrate the vertical stretch of the fabric 23 when a strain 25 is placed on the lower button 28. It will be observed that the pull on the button 28 has stretched the fabric 23 downwardly and that this stretch of the fabric 23 has relieved the front section 11 of the waist, and the buttonhole, not shown, which held the button 28, from strain. The vertical stretch of the fabric 23 also relieved the button 28 and its securing tape 27 from strain. A 30 strain placed on the button 28 is exerted through the entire width of the band of fabric 23. A strain on the upper button 25 results in that portion of the band 23 above the stay-strip 24 being pulled downwardly 35 and in that portion of the fabric 23 below the stay-strip 24 yielding to the downward pull on said stay-strip and the stretching of the fabric above said strip and thereby relieving strain from the waist and from 40 the parts to which the button 26 may be connected.

One of the purposes of my invention is to provide an underwaist which would permit the bending over, stretching and exercise of

the wearer of the waist without placing strains on the buttons 26, 28, on the waist or on the garments supported therefrom, the purpose being to supply a waist which shall be yielding vertically entirely around the waistband and at the same time be of 50 such durable character as not to be impaired, by the presence of my invention, in respect to its wearing qualities. The fabric 23 is of very great advantage as a waistband in an underwaist of the kind involved herein, because of its lack of material lengthwise stretch, its ready stretchability to a material extent in a vertical direction and its natural capability to return to normal condition when strain is relieved therefrom, and in addition the waistband is of such open texture that it is cool and permits the heat of the body to escape. The underwaist of my invention is, therefore, desirable in considering the health of the 55 wearer, as well as contributing comfort in that it permits the wearer to bend over and move in any direction without having strains placed on the shoulder straps or clothing, all vertical strains, such as would be created by bending, being absorbed by the vertical stretching of the band 23.

What I claim as my invention and desire to secure by Letters Patent, is:

An underwaist of the character described comprising front, side and back sections and a waistband extending through the horizontal length of the garment and consisting of a band of knitted fabric capable of limited longitudinal yield and of material vertical yielding under strains, stay strips at the upper and lower edges and ends of said band and an intermediate stay strip secured to and extending lengthwise of said band, said underwaist having, also, button suspending tapes secured thereto at suitable points along said intermediate stay strip and along said strip at the lower edge of said band.

Signed at New York city, in the county 95 of New York, and State of New York, this 29th day of March, A. D., 1922.

OTTO BASTIANSEN.
